CHARLES T. JACOBS, OF CHATHAM, NEW JERSEY, ASSIGNOR TO THOMAS A. EDISON, INCORPORATED, OF WEST ORANGE, NEW JERSEY, A CORPORATION OF NEW JERSEY

APPARATUS FOR AMPLIFYING ELECTRIC OSCILLATIONS

Application filed July 26, 1930. Serial No. 470,788.

This invention relates to apparatus for amplifying electric oscillations and more particularly to radio frequency amplifying systems employing amplifying vacuum tubes 5 and designed to operate, without readjustments, over a relatively wide band of frequencies.

My invention has for its object the production of an improved amplifying system of 10 the class described, suitable to be used in single or multistage form or in either form in association with other types of amplifying systems, characterized by the fact that each stage is highly efficient in amplification 15 between its inferior and superior cut-off frequencies.

Another object is to provide such an amplifying system by which different frequencies within the band between the cut-off frequencies will be amplified with a highly satisfactory degree of uniformity.

A further object of my invention is to provide such an amplifying system suitable for production in quantity without the necessity 25 for extracting limits on the electrical characteristics of its components. Other and allied objects will more fully appear from the following specification and the appended claims.

In the detailed description of my invention hereinafter set forth, reference is had to the accompanying drawings, of which

Figure I is a diagrammatic view of a single stage amplifier embodying my invention in one form;

Figure II is a typical amplification-frequency characteristic of such a stage of amplification under certain conditions;

Figure III is a diagrammatic view of a single stage amplifier embodying my invention in a slightly modified form;

Figure IV is a diagrammatic view of a single stage amplifier embodying my invention in another modified form;

Figure V is a similar view illustrating a modification in shielding of certain components of my invention; and

Figure VI is a typical amplification-frequency characteristic of a stage of amplifica-

tion embodying my invention under certain and in general preferred conditions.

In the past it has been customary in securing radio frequency amplification over a wide band of frequencies without readjustments to couple the amplifying vacuum tubes employed, each to its successor or to any other succeeding work circuit, such as a vacuum tube detector or crystal detector circuit, by means of a single transformer, having 55 primary and secondary windings very tightly coupled to each other. Associated with the primary inductance of such a transformer are its own distributed capacity, the output capacity of the preceding vacuum tube and 60 stray capacities produced by the wiring, shielding and the like. Similarly associated with the secondary inductance of such a transformer are its own distributed capacity, 65 the input capacity of the succeeding vacuum 70 tube or other work circuit and other stray capacities. By virtue of these capacities associated with the windings two tightly coupled resonant circuits are formed.

A suitable measure of the amplifying merit 75 of such a system is the ratio between the amplified voltage at the input of the tube or other work circuit following the transformer and the voltage, to be amplified, on the grid of the tube preceding the transformer. This 80 ratio may be termed the amplification per stage and, for a stage employing the transformer described, provided the natural resonant frequencies of the primary and secondary circuits, each viewed separately, are 85 the same, is approximately given by

$$\frac{Gm K}{8\pi^3 F^3 C^2 L \cdot f(N, K, F)} \quad (1)$$

wherein Gm is the mutual conductance of the tube preceding the transformer, K is the coupling coefficient between primary and secondary circuits, F is the frequency, C is the total capacity and L the inductance of each of the two resonant circuits, N is the ratio 90 of resistance to inductive reactance of the primary and secondary inductances and f (N, K, F) represents a function of the resistance-reactance ratio, the coupling coefficient and the frequency. 95 100

It may be shown that the effective value of this function, if K is greater than N , is at a minimum of two values of F ; that its value rises sharply at frequencies higher than the higher and lower than the lower of these two values of F ; that it is at a maximum at a frequency intermediate these two values of F and that if N and K remain constant with varying values of F the two minimum values of the function are equal. The terms "minimum" and "maximum" are herein used in their differential sense as denoting values at which the first derivative of the function with respect to frequency changes its sign and not in the sense of single absolute greatest and least values. Since this function appears in the denominator of (1), a system of this character tends to have two peaks of amplification separated by a "valley", or region of lower amplification, and accompanied by sharp cut-offs at frequencies slightly outside the band between the two peaks. The higher frequency peak, however, tends to be of a much lower order than the lower frequency peak, due to the F^3 term in the denominator of (1), which term denotes discrimination against amplification at higher frequencies.

To overcome or reduce this discrimination it is common practice to introduce capacity between the primary and secondary windings of the transformer and to wind or connect the secondary in reversed direction with respect to the primary. This effects a form of capacitive coupling between the primary and secondary circuits of a nature which favors amplification at the higher frequencies, which amplification for practical purposes is additive to the amplification expressed by (1), the total amplification becoming therefore less affected by the F^3 term in (1). Other common practice is to wind the primary and/or secondary with wire of relatively high resistance and/or to introduce iron or like material into the field of the coils. This practice greatly increases the minimum values of the function $f(N, K, F)$ by its effect on N without greatly increasing the maximum value, thus reducing the disparity between the amplification of the system at the peak frequencies and the amplification at intermediate frequencies. It furthermore may be made to an extent to cause the value of N and thereby the value of the function $f(N, K, F)$ to be appreciably greater at the low frequency peak than at the high, further reducing the disparity in amplification at the two peak frequencies.

In the practice of my invention I employ, instead of a single transformer, two transformers and a capacity, disposed in such a manner as to couple a vacuum tube to a succeeding vacuum tube or other work circuit in cascade through a system comprising three resonant circuits; for example, as shown in

Figure I, wherein V_1 is an amplifying tube, and V_2 is the next succeeding vacuum tube, operating either as a linear amplifier or as a demodulator or detector. V_1 is shown as a tetrode having cathode F_1 , control grid G_1 , screening grid N_1 and anode A_1 . B_1 is a D. C. source of anode current and screening grid potential for tube V_1 . T_1 and T_2 are transformers having primaries P_1 and P_2 , secondaries S_1 and S_2 and primary-secondary capacities C_4 and C_5 respectively, the transformers being in non-inductive relation to each other. The non-inductive relation may be produced, if desired, by shields or cans B_{11} and B_{21} , these being connected to the cathode systems of tubes V_1 and V_2 as at points Y_1 and Y_2 or to some point or points substantially of the same radio frequency potential as such cathode systems. C_1 represents the total capacity in shunt to the primary P_1 of transformer T_1 , comprising the distributed capacity of the winding P_1 , the output capacity of the tube V_1 , parallel stray capacities as to the shield B_{11} , and physically introduced capacity if desired. Similarly C_2 represents the total capacity in shunt to the secondary S_2 of the transformer T_2 . C_3 is a condenser, forming, with S_1 and P_2 , a closed resonant circuit, V_2 shown is an amplifying or detecting tube having input electrodes F_2 and G_2 , F_2 being its cathode, and such source, B_2 , of input electrode D. C. potential difference as may be required for proper operation of the tube V_2 . It will be understood, however, that V_2 may comprise any other form of work circuit, such as a crystal detector circuit.

If the three resonant circuits C_1-P_1 , $S_1-C_3-P_2$ and S_2-C_2 have the same natural frequency, if P_1 equals S_2 and the inductance of each is noted by L_1 , and if K_1 denotes a similar coupling coefficient both of circuit C_1-P_1 to circuit $S_1-C_3-P_2$ and of circuit $S_1-C_3-P_2$ to circuit S_2-C_2 , the per stage amplification is given approximately by

$$\frac{Gm K_1^2}{8\pi^3 F^3 C_1^2 L_1^2 \cdot f_1(N, K_1, F)} \quad (2)$$

wherein the significance of the symbols is the same as for expression (1), except for the special symbols noted above and for the new function $f_1(N, K_1, F)$, which is of higher order than the corresponding function in (1).

It may be shown that the effective value of the function $f_1(N, K_1, F)$ provided K_1 is greater than $6\frac{1}{2} N$, is a minimum for three values of F ; that its value rises sharply at frequencies higher than the highest and lower than the lowest of these three values of F and that its value is at a maximum for two other values of F intermediate the first mentioned three values. It may further be shown that if N and K_1 remain constant with

varying values of F , the two maximum values of the function are equal, the highest and lowest frequency minimum values of the function are equal and the middle frequency minimum is the lowest value to which the function attains. Thus a system of this characters tends to have three peaks of amplification, shown as 11, 13 and 15 in the typical or illustrative curve of Figure II, the middle frequency peak 13 being the highest, separated by amplification "valleys" 12 and 14 and accompanied by sharp cut-offs occurring slightly outside the band between peaks 11 and 15. The less efficient amplification at valley 14 and peak 15 than at valley 12 and peak 11, respectively, is due to the F^3 term in the denominator of (2).

I have found it desirable in the practice of my invention to wind the transformers of moderately high resistance wire, such as fine copper wire, for the purpose of reducing generally the disparity of amplification between the peaks 11, 13, 15 and the valleys 12, 14, as well as for the purpose of reducing to a degree the disparity of amplification between the valleys 12 and 14 and between the peaks 11 and 15. I have further found it desirable to utilize inherent capacity C_5 between the primary and secondary of transformer T_2 , together with winding or connection reversal of the secondary S_2 of this transformer with respect to the primary P_2 . I have found, however, that the effect of primary-secondary capacity C_4 in transformer T_1 is of a very much lower order than that of capacity C_5 in transformer T_2 , but that in order to obtain a slight beneficial result from the use of this capacity the secondary S_1 of the transformer T_1 should be neither wound nor connected, or else should be both wound and connected, in reversed direction with respect to the primary P_1 . It should be noted that to obtain best results from the use of either C_5 or C_4 or both, the circuit $S_1-C_2-P_2$ should be connected to the cathode systems of tubes V_1 and V_2 , as by the connection in Figure I between points Z and X , or to any other point in the system which is substantially of the same radio frequency potential as such cathode systems.

In Figure III, I show an alternative arrangement wherein auto-transformers U_1 and U_2 are substituted for the true transformers T_1 and T_2 of Figure I. Other symbols have the same significance in the two figures. It will be understood, of course, that combinations of one true- and one auto-transformer may also be used as shown, for example, in Fig. IV, in which figure the true transformer is shown as preceding the auto-transformer.

In Figure V, I show two auto-transformers as in Figure III, excepting that they are not shielded from each other by separate shields, being positioned in substantially non-induc-

tive relation to each other and being wound, if desired, in such relation on a common winding form. A single shield, shown as B, may be used around both, if desired. It will be understood, of course, that two true combinations of one true- and one auto-transformer may be similarly utilized without separate shielding. In either Figure III, Figure IV or Figure V the basic circuit arrangements and the analyses are the same as in Figure I, excepting for the omission of C_4 and/or C_5 in arrangements using two auto-transformers or one auto-transformer, respectively.

In many cases it is desirable to employ one or two auto-transformers for structural or economic reasons, in which cases the benefit of the use of C_4 and/or C_5 is, of course, lost. I have further found that in many cases wherein one or two true transformers are used the benefits to be desired from the use of C_4 and/or C_5 , with the appropriate direction of winding and/or connection of the secondaries as outlined above, are insufficient or otherwise unsatisfactory as a means of overcoming discrimination in general against the amplification of higher frequencies, which manifests itself particularly in low amplification in valley 14. I have found that in such cases greater uniformity of low and high frequency amplification may be secured over a given band by resonating two of the circuits to a slightly higher frequency and the remaining circuit to a lower frequency than that one frequency to which each circuit would be resonated in the case of similar natural periods for all three. When this is done it is distinctly preferable to raise slightly the frequencies of circuits C_1-P_1 and S_2-C_2 and to lower that of the middle circuit $S_1-C_3-P_2$, due to the reduced degree to which the constants of the middle circuit affect the amplification characteristics. Such shifting of circuit frequencies may be made to change the curve of the system from one of the type of Figure II to one of the type of Figure VI, a more symmetrical and a preferable curve, of higher minimum amplification.

It may be shown that the stiffness, or total inductance-capacity ratio, of the middle circuit is almost without effect on the amplification characteristics. In this respect the middle circuit is unlike the first and third circuits, each of which should, for maximum amplification, be made as stiff as possible by the use of high inductance and low capacity values. It is desirable that each of the inductances S_2 and P_1 of the middle circuit be resonated, by its own distributed capacity and stray capacities as to the shield or shields, to a frequency very much higher than the highest frequency of the band over which the system is designed to operate and for that reason it is desirable to use rela-

tively low inductance values for both S_1 and P_2 , maintaining the natural frequency of circuit $S_1-C_3-P_2$ at the frequency desired by the use of a relatively high capacity value 5 for C_3 .

If all three circuits separately have the same natural frequency F_0 , the frequencies of peaks 11, 13 and 15 in Figure II are respectively given approximately by

$$10 \quad \frac{F_0}{\sqrt{1+2\frac{1}{2}K_1}}, \quad F_0 \text{ and } \frac{F_0}{\sqrt{1-2\frac{1}{2}K_1}} \quad (3)$$

This assumes similar coupling coefficients, each K_1 , between the first and middle circuits 15 and between the middle and third circuits. Thus the frequencies of the extreme peaks and as a result thereof the cut-off frequencies are determined for any given natural frequency F_0 by the coupling co-efficients.

20 If one of the circuits, however, and in particular the middle circuit, be resonant to a somewhat lower frequency than the other two, control of the natural frequency of this circuit produces a marked control of the frequency of the low frequency peak 11 and an appreciable control of the frequency of the peak 15, both of these frequencies shifting in the same direction with any change of the natural frequency of the middle circuit. I 25 have found that by proper control of the value of C_3 and preferably by utilizing therefor a capacity adjustable within limits the frequency response band of the system may readily be shifted over small ranges.

30 This is very desirable in quantity production of systems for the amplification of radio frequencies over wide bands as it permits less exacting manufacturing tolerances for the values of the component parts.

40 It will be understood that although I have shown and described my invention in single stage form, as many stages thereof as desired may be used, in combination, if further desired, with other types of amplifying stages.

45 It will be further understood that changes may be made in the physical and electrical choice and disposition of components and of the precise manner of employment thereof, without departing from the scope or spirit 50 of the appended claims.

I claim:

1. In a system for the amplification of radio frequency currents in combination a 55 vacuum tube, a succeeding work circuit and coupling means connected in the output circuit of said vacuum tube and to the input of said succeeding work circuit for coupling said tube and said work circuit in cascade, said coupling means comprising, with the output capacity of vacuum tube and the input capacity of said work circuit, three tightly coupled cascaded resonant circuits, of which two have substantially the same 60 resonant frequency and the other a substantially different resonant frequency, whereby 65

with fixed adjustments of all elements thereof of amplification may be secured over a wide band of frequencies.

2. In a system for the amplification of radio frequency currents in combination a 70 vacuum tube, a succeeding work circuit and coupling means connected in the output circuit of said vacuum tube and to the input of said succeeding work circuit for coupling said tube and said work circuit in cascade, 75 said coupling means comprising, with the output capacity of vacuum tube and the input capacity of said work circuit, three tightly coupled cascaded resonant circuits, of which two have substantially the same resonant frequency and the other a substantially lower resonant frequency, whereby with fixed adjustments of all elements thereof of amplification may be secured over a wide 80 band of frequencies.

3. In a system for the amplification of radio frequency currents in combination a 85 vacuum tube, a succeeding work circuit and coupling means connected in the output circuit of said vacuum tube and to the input of said succeeding work circuit for coupling said tube and said work circuit in cascade, 90 said coupling means comprising, with the output capacity of vacuum tube and the input capacity of said work circuit, three tightly coupled cascaded resonant circuits, of which the first and last are characterized by a relatively high, and the middle circuit by a relatively low inductance-capacity 95 ratio, whereby with fixed adjustments of all elements thereof of amplification may be secured over a wide band of frequencies.

4. In a system for the amplification of radio frequency currents in combination a 100 vacuum tube, a succeeding work circuit and coupling means connected in the output circuit of said vacuum tube and to the input of said 105 succeeding work circuit for coupling said tube and said work circuit in cascade, said coupling means comprising, with the output capacity of vacuum tube and the input capacity of said work circuit, three tightly coupled cascaded resonant circuits, of which the first and last 110 have substantially the same resonant frequency and the middle circuit a substantially lower resonant frequency, whereby with fixed 115 adjustments of all elements thereof of amplification may be secured over a wide band of frequencies.

5. In a system for the amplification of radio frequency currents in combination a 120 vacuum tube, a succeeding work circuit and coupling means connected in the output circuit of said vacuum tube and to the input of said succeeding work circuit for coupling said tube and said work circuit in cascade, said coupling means comprising, with the output capacity of vacuum tube and the input capacity of said work circuit, three tightly coupled cascaded resonant circuits, of which the 125 first and last have substantially the same resonant frequency and the middle circuit a substantially lower resonant frequency, whereby with fixed 130 adjustments of all elements thereof of amplification may be secured over a wide band of frequencies.

first and last are characterized by a relatively high inductance-capacity ratio and have substantially the same resonant frequency and the middle circuit is characterized by a relatively low inductance-capacity ratio and has a substantially lower resonant frequency than that of the first and third circuits, whereby with fixed adjustments of all elements thereof amplification may be secured over a wide 10 band of frequencies.

6. In a system for the amplification of radio frequency currents in combination a vacuum tube, a succeeding work circuit and coupling means connected in the output circuit 15 of said vacuum tube and to the input of said succeeding work circuit for coupling said tube and said work circuit in cascade, said coupling means comprising two transformers in substantially non-inductive relation each 20 to the other, each having tightly coupled primary and secondary windings, said transformers having one terminal of one winding of each connected together and having the opposite terminals of said windings connect- 25 ed through a capacity to produce three cascaded resonant circuits, at least one of said transformers having capacity between the primary and secondary windings thereof and the secondary of the second transformer in 30 the cascade being reversed with respect to the primary thereof, whereby with fixed adjustments of all elements thereof amplification may be secured over a wide band of frequencies.

35 7. In a system for the amplification of radio frequency currents in combination a vacuum tube, a succeeding work circuit and coupling means connected in the output circuit of said vacuum tube and to the input of said 40 succeeding work circuit for coupling said tube and said work circuit in cascade, said coupling means comprising one auto-transformer of a high degree of coupling and one transformer having tightly coupled primary 45 and secondary windings in substantially non- 50 inductive relation to said auto-transformer said transformer having one terminal connected to said auto-transformer directly and having the other terminal of said winding 55 connected to said auto-transformer through a capacity to produce three cascaded resonant circuits, the transformer following the auto- 60 transformer in the cascade and having capacity between the primary and secondary 65 windings thereof and the secondary of the transformer being reversed with respect to the primary thereof, whereby with fixed 70 adjustments of all elements thereof amplification may be secured over a wide band of frequencies.

This specification signed this 24th day of July, 1930.

CHARLES T. JACOBS.

CERTIFICATE OF CORRECTION.

Patent No. 1,867,746.

July 19, 1932.

CHARLES T. JACOBS.

It is hereby certified that error appears in the printed specification of the above numbered patent requiring correction as follows: Page 1, line 25, for "extracting" read exacting; page 2, line 3, for "of" first occurrence read for; line 24, for "lower" second occurrence read low; and line 123, before the article "a" insert the word at; page 3, lines 6 and 7, for "characters" read character; and line 71, for the words "combinations of" read transformers or; and that the said Letters Patent should be read with these corrections therein that the same may conform to the record of the case in the Patent Office.

Signed and sealed this 29th day of November, A. D. 1932.
